UNITED STATES PATENT OFFICE.

EDWARD F. SHIPMAN, OF WOODHAVEN, NEW YORK.

FUSIBLE LINK.

1,295,220.

Specification of Letters Patent.

Patented Feb. 25, 1919.

Application filed August 18, 1917. Serial No. 187,000.

To all whom it may concern:

Be it known that I, EDWARD F. SHIPMAN, a citizen of the United States, residing in Woodhaven, county of Queens, and State of New York, have invented a certain new and useful Fusible Link, of which the following is a specification.

This invention is a fusible link adapted, more particularly, for use with automatic 10 sprinklers, although not specifically limited to this application. The object of the invention is to provide a fusible link which will be extremely strong under tension and quickly 15 disruptable upon the application of a pre-determined degree of heat.

A further object of the invention is to improve upon links heretofore employed by so constituting the structure that the parts may be readily stamped up from sheet metal in a 20 most economical and efficient manner.

With the foregoing objects in mind, the preferred embodiment of the invention consists of two juxtaposed tension members which are united by fusible solder, and between which members is positioned a key-piece in the form of a circular disk seated in correspondingly shaped depressions or 25 pockets in the respective tension members. Spacing projections are preferably provided 30 on the inner face of each member and are adapted to contact with the adjacent face of the other member to maintain said members in spaced relation for the purpose of facilitating the assembling operation and the application of fusible solder thereto.

Features of the invention, other than those specified, as well as the advantages thereof, will be apparent from the hereinafter detailed description taken in conjunction with 40 the accompanying drawing.

In the accompanying drawing I have illustrated different practical embodiments of the invention, but the constructions therein shown are to be understood as illustrative, 45 only, and not as defining the limits of the invention.

Figure 1 is a perspective view of a link embodying the present invention.

Fig. 2 is a central, longitudinal section therethrough.

Fig. 3 is a perspective view of the key-piece employed, and

Figs. 4 and 5 are views like unto Fig. 2, but taken through links of slightly modified 55 constructions.

Referring to the drawing, A and A' design-

nate two tension plates which may be of different peripheral contours, but are here shown as having substantially parallel sides and one rounded end. In the rounded ends 60 of the plates are formed apertures a a', and through these apertures are adapted to extend chains, cables, or other devices which it is desired that the link shall normally maintain in spaced relation at the point of application of the link. In order that the aperture a' may not be fouled by plate A, said plate is provided at the end adjacent said aperture with a reentrant portion B, and plate A' is similarly formed at its opposite 70 end, so that chains or cables, passing through apertures a and a', will not be interfered with by the adjacent plates.

Positioned substantially centrally of plates A and A', and formed in the adjacent surfaces thereof, are circular depressions or seats C C', whereby, when the plates are brought into juxtaposition, as shown in Figs. 1 and 2, a substantially circular chamber or space will be formed by the combination of 80 the two pockets. In this chamber or space is positioned a key-piece D, in the form of a metallic disk, shown in detail in Fig. 3.

The formation of the pockets C and C' and the manner of their positioning in the 85 plates A and A', respectively, may vary, as shown in Figs. 2, 4 and 5. As shown in Fig. 2, the pockets C and C' are, at their sides respectively adjacent opposite ends of the link, substantially equal in depth to the 90 thickness of key disk D, and taper off in depth toward the opposite ends of the link, so that the faces of pockets C C' intersect with the inner faces of plates A A', respectively, after the manner shown in Fig. 2. 95 With this construction, key disk D, when positioned within the chamber formed by pockets C and C', is tilted, relative to the axis of the link, to an appreciable extent, one edge of disk D lying wholly within plate C 100 and the diametrically opposite portion thereof lying wholly within plate C'.

In Fig. 4 complete, cylindrical pockets are shown as impressed in the surface of both plates, the faces of said pockets lying entirely beneath the adjacent faces of the plates, and not intersecting therewith as in the construction of Fig. 2. The structure of Fig. 4 differs from that of Fig. 2 in that the key disk, while equally housed within the 110 pockets of both plates, is not tilted to such an appreciable extent as is the case in Fig.

2, and greater tension will be required to separate the plates after the solder has been melted. In other words, while the construction of Fig. 2 may separate when the solder 5 has become softened, but not entirely melted, the structure of Fig. 4 will require that the solder become softer before the link will be disrupted.

In the construction of Fig. 5, the pockets 10 are shown as depressed squarely into the respective plates, so that the faces of the pockets lie in planes parallel to the faces of the plates. In such a construction, the key disk D will not be tilted, but its faces will 15 be parallel to the faces of the plates. While a link of this character will withstand a greater tension than the constructions of Figs. 2 and 4, it will require that the solder be practically melted before the link will be 20 disrupted.

It will, of course, be understood that the link is "floated" with fusible solder; and, in order to facilitate the assembling and soldering operations, each plate is preferably provided with inwardly extending projections 25 E formed by stamping out the plates, as shown at e. These projections serve to space the plates slightly apart, so that the edges thereof may be properly soldered. In the 30 accompanying drawing, in the interest of clearness, the plates are shown as spaced an appreciable distance apart, and considerable clearance is shown between the disk D and the pockets which house the same. It will be 35 understood that, in practice, this space is much less than as shown, the plates being brought into substantially face-abutting relation.

An important consideration in the manufacture and use of the link of this invention 40 resides in the fact that the pockets are formed in such a manner that the edges c thereof are substantially sharp edges. The advantage of this construction is that, when 45 assembled, tension is applied to the link which positions the disk and causes the outer or sharp edges of the pockets to grip the disk on a line flush with the inner faces of the plates. By this construction, the off-set and 50 thickness of the key disk are reduced to a minimum, forming a very rigid and strong construction.

The use of a circular disk is very important, in that practically the entire circumference of the disk carries the tension on the plates, since substantially said entire circumference forms a bearing surface which seats in the corresponding parts of the respective pockets. Thus, when the plates are 55 assembled, the disk has a greater portion of its circumference in bearing contact, but, the moment the link starts to separate, the bearing is transferred to the knife-like edges of the pockets and a practically frictionless 60 bearing results. The disk in this position 65

is very unstable and is free to turn on its axis in rotary movement, or tilt upon its edges, so that it will open very quickly and will readily overcome any mechanical interference, such as corrosion attacking one edge 70 of the link and serving to hold the same stronger than the other edge thereof. In the case of greater corrosion at one edge than the other, slight lateral or rotary movement of the disk will result during the disruption of the parts, and this moment will assist in breaking or overcoming such mechanical resistance.

A marked advantage inherent in the use of a circular disk as a key-piece is the ease 80 with which the pockets may be stamped through the use of a circular die. Such a die will allow of maximum depth without any tendency to tear or break the plates. Through the use of a circular disk, moreover, a much 85 greater bearing surface, and consequently more complete distribution of the load, result, and a stronger link may be made from lighter material than could possibly be the case in such links as employ elongated bars 90 which extend longitudinally of the link and carry the load at their ends, or similar bars which extend transversely of the link and only carry the load at their edges. The positioning of the circular disk in the center of 95 the link, where it is protected from the effect of corrosion, is a marked advantage over links employing a tilting bar or cylindrical pin extending transversely of the link and from face to face thereof, since, in the latter 100 case, the ends of the bar or pin are exposed to the action of corrosion and the link will not open so freely after the solder has become softened.

It has heretofore been suggested to employ spherical key-pieces, and an example of such construction is shown in the patent to Perry, No. 1,208,200, wherein the key-piece is in the form of a ball bearing. In a construction of this character, the solder 110 carries substantially all of the load, since the plates of the link engage with the rounded faces of the ball and do not seat in flat, abutting contact with the key-piece, as is the case with the present invention. It is 115 necessary, in links embodying the ball bearing key-piece, to provide some other means for strengthening the link, and this Perry accomplishes by means of bent-up ears 120 which are adapted to be covered with solder. In contradistinction to the sliding engagement between the plates and the key-piece of the Perry patent, and other prior structures embodying the ball bearing principle, the disk of this invention provides a positive, flat shoulder engagement which carries the load on the link, the solder serving only 125 to maintain the plates against the tilting action of the key. The present invention thus embodies all the benefits of such rotary 130

movement as are present in the ball bearing construction, without embodying the marked objectional features thereof, and is considerably stronger and will withstand far greater 5 tension than links of the ball bearing type, while employing much less material and relying entirely upon the key-piece, to the exclusion of extraneous projections, etc.

Having thus fully described the invention, what I claim as new, and desire to secure by Letters Patent, is:

1. A fusible link embodying two complementary tension plates, each of which is provided in its inner face with a circular depression or pocket, said depressions being adapted to register with each other when the plates are placed in lapped relation, whereby a circular chamber is formed between the plates, a circular disk occupying 15 said chamber, and fusible solder uniting the tension plates.

2. A fusible link embodying two lapped tension plates, a circular disk housed between said plates and within circular depressions formed in the inner faces of said plates, and fusible solder uniting said plates.

3. A fusible link embodying two lapped members, each of which is provided with a circular depression, said depressions registering to form a substantially closed, rela-

tively shallow, circular chamber, a circular disk occupying said chamber, and fusible solder uniting the plates.

4. A fusible link embodying two lapped tension plates, a flat circular disk housed 35 within depressions formed in the inner faces of said plates, said depressions intersecting with the inner faces of their respective plates to form sharp edges, and fusible solder for uniting the plates, whereby, when 40 the solder is melted, the plates swing apart on the disk, employing said sharp edges as fulcrums.

5. A fusible link embodying a pair of lapped tension plates, each of which is provided with a circular depression having sharp edges, said depressions registering to 45 form a substantially closed, relatively shallow, circular chamber, a flat circular disk occupying said chamber, and fusible solder 50 uniting the plates, whereby, when the solder is melted, the disk tilts and the plates swing apart, with the circumference of the disk bearing on the sharp edges of the pockets, the disk being free to turn on its axis during the tilting operation of said disk.

In testimony whereof I have signed my name to this specification.

EDWARD F. SHIPMAN.
